UNITED STATES PATENT OFFICE.

OLIVER H. ERNST, OF CRESTLINE, OHIO.

GAS-STOVE.

SPECIFICATION forming part of Letters Patent No. 739,780, dated September 22, 1903.

Application filed May 25, 1903. Serial No. 158,688. (No model.)

To all whom it may concern:

Be it known that I, OLIVER H. ERNST, a citizen of the United States, residing at Crestline, in the county of Crawford and State of Ohio, have invented new and useful Improvements in Gas-Stoves, of which the following is a specification.

This invention relates to gas-stoves, and has for its object to provide a heater of this type of a simple and practical construction, while at the same time comprising means for increasing the heating and radiating surfaces to the maximum.

To this end the invention contemplates a gas-stove structure of a convertible type whereby the same may be utilized either as a grate-stove for ordinary fuel or in connection with gas-burners and yet being so constructed as to utilize the heat to the greatest possible advantage, but permitting of the escape of the products of combustion from the escape-pipe.

A further object of the invention is to so construct the stove as to be of special utility as a gas-heater employing natural or artificial gas for heating purposes and providing for circulating a body of air throughout the entire length of the stove-body and subjecting it during such circulation to the heated products without contamination with the latter, thus insuring a maximum heating effect and providing for the discharge of pure heated air into the room to be heated.

With these and many other objects in view, which will more readily appear as the nature of the invention is better understood, the same consists in the novel construction, combination, and arrangement of parts, which will hereinafter be more fully described, illustrated, and claimed.

The essential feature of the invention involved in the novel manner of associating the hot-air chamber or pipe with the deflecting-diaphragms is necessarily susceptible to structural modification without departing from the scope of the invention; but a preferred embodiment of the latter is shown in the accompanying drawings, in which—

Figure 1 is a vertical central longitudinal sectional view of a gas-stove embodying the present invention. Fig. 2 is a cross-sectional

view on the line 2 2 of Fig. 1. Fig. 3 is a similar view on the line 3 3 of Fig. 1.

Like reference-numerals designate corresponding parts throughout the several figures 55 of the drawings.

In carrying out the invention the operative parts of the heater are inclosed within an upright exterior stove-casing, (designated in the drawings by the numeral 1 and of the usual sheet-metal formation.) The said exterior stove-casing 1 may be of a cylindrical, elliptical, or other suitable configuration in cross-section, as it is only necessary to employ a tubular casing 1 open throughout from top 65 to bottom to properly accommodate the other elements of the stove.

The exterior casing 1 is suitably mounted at the lower end thereof upon an open or hollow base-section 2, surmounted upon the 70 supporting-legs 3, which serve to hold the bottom of the stove above the level of the floor to permit of the ready ingress of the air to be heated. Immediately above the plane of the open or hollow base-section 2 the exterior stove-casing 1 is of an expanded form to provide a fire-pot chamber 4, which accommodates the wire. In order to make the stove of a convertible type, the fire-pot chamber 4 is provided within the bottom portion thereof 75 with any suitable type of fuel-grate 5, whereby ordinary fuel may be employed in the stove, and below the plane of said grate is formed with a pendent box extension 6, constituting a burner-pit which accommodates 80 one or a plurality of gas-burners 7, designed to burn artificial or natural gas, the flame from which projects into the fire-pot chamber 4, so that the heat therefrom will serve to heat up the air drawn into and circulated upward through a central hot-air chamber 8. When the grate of the stove is utilized for ordinary fuel, it will be understood that the pendent box 6 also constitutes an ash-receptacle and that the same is removable by bolts 90 6^a. Also there are arranged at the sides of said receptacle perforations 6^b for the admission of air.

The central hot-air chamber 8 is in the form of a cylindrical or elliptical pipe extending 100 longitudinally throughout the entire length of the stove-casing and having its lower open

inlet end 9 projecting through the burner-pit 6 and exposed within the open or hollow base-section 2, so as to be free to receive the supply of air which is to be heated up and circulated 5 out into the room. The upper open discharge end 10 of the hot-air chamber or pipe 8 is fitted to and opens through an imperforate closure-head 11, arranged horizontally within the upper end portion of the stove-casing 1 10 and constituting a closing-diaphragm for that end of the casing, so as to completely confine the products of combustion within the body portion of the casing about the hot-air chamber or pipe 8. The said upper end of the exterior stove-casing 1 is also surmounted by an ornamental grille or perforate distributing-top 12, through the openings or interstices of which the heated air discharged from the hot-air chamber passes in the room to be heated. 15 20 To insure a proper deflection of the heated products, so that the same may be uniformly passed through the grille top 12, the latter has fitted centrally to the under side of its top portion a pendent deflecting-dome 13 of a semispherical form and lying centered above the upper discharge end 10 of the hot-air chamber or pipe.

One of the distinctive features of the present invention resides in means for so retarding the passage of the heated products through 30 the heating-space 14 between the stove-casing and the interior hot-air chamber as to secure a thorough and maximum heating effect upon the chamber or pipe 8. This is preferably accomplished by the employment of a plurality of deflecting-diaphragms 15, arranged in the said heating-space 14 at intervals between the fire-pot chamber 4 and the imperforate closure-head 11 of the stove-casing. 35 Any desired number of the deflecting-diaphragms 15 may be employed; but the alternating order thereof always remains the same to provide for compelling the heated products to pass in a zigzag direction from 40 one side of the casing to the other in its upward circulation toward the escape-opening 16, formed in the casing side at or contiguous to the top thereof, said escape-opening 16 having a suitable pipe connection 17 there- 45 with.

Each of the deflecting-diaphragms 15 corresponds in general form to the cross-sectional contour of the stove-casing 1 and suitably fitted at its edges thereto, so as to prevent 50 the leakage of the heated products except at the point provided therefor. Also each of said deflecting-diaphragms 15 is formed with a horizontal section 18, joined tightly to the casing 1, and also provided with 55 a pipe-opening 19, receiving the hot-air chamber or pipe 8, and the edges of which opening tightly fit the said chamber or pipe and rest upon an annular supporting ring or collar 20, fitted to and encircling the chamber or pipe 60 65 8. At one side of the plane of the vertical air chamber or pipe 8 each diaphragm 15 has extended from its horizontal section 18 a

downwardly-curved baffle-apron 21, having a flanged end portion 22, terminating short of the adjacent side of the casing 1 to provide 70 an interval 23, constituting a circulating-passage for the heated products. By reason of the diaphragms 15 being arranged with their baffle-aprons 21 disposed alternately at opposite sides of the stove-casing the circulating-passages 23 are necessarily disposed in alternate order at opposite sides of the casing, thus compelling the circulation referred to. 75

An additional baffling or retardation of the heated products is accomplished through the 80 medium of an auxiliary upright baffle-wall 24, fitted to the horizontal section of the uppermost diaphragm 15 adjacent to the escape-opening 16.

While a single hot-air chamber or pipe 8 85 has been described and illustrated, still it will be understood that a plurality of such chambers or pipes could be employed without affecting the invention.

Changes in the form, proportion, and minor 90 details of construction may be resorted to without departing from the spirit of the invention or sacrificing any of the advantages thereof.

Having thus described the invention, what 95 is claimed, and desired to be secured by Letters Patent, is—

1. In a stove of the class described, an upright casing provided at its upper end with an imperforate head and an open distributing-top, a hot-air chamber or pipe extending longitudinally within the casing and opening through the imperforate head thereof into the open top, and deflectors arranged in the heating-space between the casing and the air chamber or pipe and having baffle-aprons terminating short of the adjacent side of the casing.

2. In a stove of the class described, the upright casing having at the lower end thereof a fire-pot chamber provided with a fuel-grate and an offset burner-pit receiving gas-burners, an imperforate closure-head for the upper end of the casing, an open distributing-top surmounting the casing and provided with a centrally-arranged pendent deflecting-dome, a hot-air chamber or pipe extending longitudinally within the casing, and opening at its upper end through the closure-head beneath the deflecting-dome, the lower end of said chamber or pipe extending through the burner-pit and opening into the base of the stove, and deflectors arranged in the heating-space between the casing and the air chamber or pipe.

3. In a stove of the class described, the upright casing provided at its upper end with an imperforate closure-head and also with an open distributing-top, said casing being further provided at or contiguous to its upper end with an escape-opening, a hot-air chamber or pipe extending longitudinally within the casing and opening at its upper end into the open distributing-top, a series of deflect-

ing-diaphragms arranged within the casing about the hot-air chamber or pipe and each provided with a horizontal section fitting the casing and at one side of the hot-air chamber or pipe with a downwardly-curved flanged baffle-apron terminating short of the adjacent side of the casing to provide an intervening circulating-passage, the series of circulating-passages being disposed alternately at opposite sides of the casing, and an auxiliary baffle-wall supported by the uppermost diaphragm adjacent to the escape-opening.

4. In a stove of the class described, an upright casing provided at its upper end with an imperforate head and an open distributing-top, a hot-air chamber or pipe extending longitudinally within the casing and opening through the imperforate head thereof into the open top, and a series of deflecting-diaphragms arranged within the casing about the hot-air chamber or pipe and each provided with a horizontal section fitting the casing and at one side of the hot-air chamber or pipe with a downwardly-curved flanged baffle-apron terminating short of the adjacent side of the casing to provide an intervening circulating-passage.

5. In a stove of the class described, an upright casing provided at its upper end with an imperforate head and an open distributing-top, a hot-air chamber or pipe extending longitudinally within the casing and opening through the imperforate head thereof into the open top, an ash-receptacle surrounding the lower end of said chamber or pipe with the sides thereof perforated and means exterior to the upright casing for disengaging said ash-receptacle therefrom.

6. In a stove of the class described, an up-

right casing provided at its upper end with an imperforate head and an open distributing-top, a hot-air chamber or pipe extending longitudinally within the casing and opening through the imperforate head thereof into the open top, and an ash-receptacle surrounding the lower end of said chamber or pipe having flanges for engagement by exterior fastening means with said upright casing.

7. In a stove of the class described, an upright casing provided at its upper end with an imperforate head and an open distributing-top, a hot-air chamber or pipe extending longitudinally within the casing and opening through the imperforate head thereof into the open top, deflectors arranged in the heating-space between the casing and the air chamber or pipe, downwardly-curved flanged baffle-aprons and an ash-receptacle surrounding the lower end of said receptacle or pipe.

8. In a stove of the class described, an upright casing provided at its upper end with an imperforate head and an open distributing-top, a hot-air chamber or pipe extending longitudinally within the casing and opening through the imperforate head thereof into the open top, deflectors arranged in the heating-space between the casing and the air chamber or pipe, and an ash-receptacle surrounding the lower end of said chamber or pipe with the sides thereof perforated.

In testimony whereof I have signed my name to this specification in the presence of two subscribing witnesses.

OLIVER H. ERNST.
